UNITED STATES PATENT OFFICE.

JESSE E. WILHELM AND WILLIAM W. BONFIELD, OF CLEVELAND, OHIO, ASSIGNORS TO THE GREAT LAKES DREDGE & DOCK COMPANY, OF CHICAGO, ILLINOIS, A CORPORATION OF NEW JERSEY.

GRIPPING DEVICE FOR WITHDRAWING SHEET-PILING.

1,221,400.

Specification of Letters Patent.

Patented Apr. 3, 1917.

Application filed February 3, 1916. Serial No. 75,941.

To all whom it may concern:

Be it known that we, JESSE E. WILHELM and WILLIAM W. BONFIELD, citizens of the United States, residing at Cleveland, in the county of Cuyahoga and State of Ohio, have invented a certain new and useful Improvement in Gripping Devices for Withdrawing Sheet-Piling, of which the following is a full, clear, and exact description, reference being had to the accompanying drawings.

This invention relates to devices for withdrawing steel sheet piles such as are used for coffer-dams. The general object of the invention is to provide a very simple, efficient device for gripping the upper portion of steel sheet piles so that a suitable raising power attached to the gripping device may withdraw the pile from the ground. In addition to simplicity and cheapness of manufacture, further objects are to provide for ready and convenient removal of the gripping device from its engagement with the pile; still another object is the provision of a large area of gripping surfaces whereby the danger of severing or distorting the metal of the pile, heretofore experienced with other gripping devices, is entirely obviated.

Our invention is hereinafter more fully described in connection with the drawings and its essential characteristics are summarized in the claims.

Referring to the drawings, Figure 1 is a perspective view of our gripping device, shown as engaging the upper portion of a sheet pile; Fig. 2 is a side elevation of our device; Fig. 3 is a horizontal section looking downwardly, taken substantially on the line 3-3 of Fig. 2; Fig. 4 is a longitudinal section through one of the jaws and gripping arms, illustrating a modified construction thereof; Fig. 5 is a transverse section on the line 5-5 of Fig. 4.

Referring to the drawings by reference numerals, 10 and 12 indicate downwardly extending arms connected at their upper ends by an integral portion 14, thus forming a bifurcated body. At the upper end of the body is shown an integral upwardly projecting eye piece 16 adapted for attaching the body to a suitable hoisting mechanism. The inner surfaces of the arms 10 and 12 each slope inwardly toward their

lower ends and are provided with longitudinal grooves 17 adapted to slidably receive tongues 18 on the outer sides of movable jaws 20 and 21. These jaws rest against the inner surfaces of the portions 10 and 12 and are preferably wedge-shaped, so that their adjacent sides may be substantially parallel. These adjacent sides are preferably provided with transverse, that is horizontal, serrations 24, adapted to grip the sides of a sheet pile such as is indicated at 25 in Fig. 1.

On the lower ends of the arms 10 and 12 are provided transverse blocks 26 and 27 secured in position by screws 28. These blocks extend inwardly beneath the lower ends of the jaws 20 and 21, normally preventing displacement or removal of the jaws. The blocks may be readily removed to permit convenient assembling of the jaws in the body. Threaded through these blocks are shown screws 30, adapted to engage the lower ends of the jaws and move the body portion with relation to the jaws, thereby providing a positive means for releasing the grip of the jaws after withdrawing a pile. While the weight of the body is usually sufficient to release the grip of the jaws, after withdrawing the pile, they sometimes become wedged tightly enough to require greater force for releasing, and these screws provide a convenient means of applying such a force.

In Figs. 1 to 3 inclusive, the tongue and groove connection between the jaws and the body is shown as of dove-tailed construction so that the jaws may maintain their normal separated position.

In Figs. 4 and 5 we have shown a modified construction of the jaw and arm which may be used when it is desired to obviate the difficulty of machining the dove-tailed grooves in the body.

The arm 12^a corresponds to the arm 12 described, and is shown as provided with a parallel-sided groove 32, into which fits the tongue 33 (corresponding to the tongue 18) on the jaw 21^a. The arm 12^a is provided with a longitudinal slot 35 opening into a larger slot 36 at the bottom of which are shoulders 37, formed parallel with the inner surface of the arm on which the jaw slides. Screws or bolts 40 rigidly engaging the jaw may extend loosely through the slot 35 and

carry at their outer ends, washers 42 beneath the heads 43 of the bolts. These washers slidably engage the shoulder 37, allowing a vertical movement of the jaw while preventing its displacement.

In operation, the device is lowered over the upper portion of a pile preferably until the connecting portion 14 rests on the top thereof and the hoisting apparatus attached 10 to the eye 16 is then operated. The weight of the jaws 20 and 21 causes them to engage the pile and the relative upward movement of the bifurcated body provides a wedging action pressing the jaws toward each other 15 with great force causing the serrations to firmly engage the pile, thereby drawing the same upwardly with the upward movement of the body. The jaws, being comparatively long and having serrations throughout their 20 length, provide for gripping the pile over a large surface, thus preventing the tearing out or distorting the web of the upper portion thereof. Incidentally the large serrated gripping surface has the advantage of wearing 25 much longer than the serrations of comparatively smaller surfaces. It is frequently inconvenient to lower the gripping over the pile a distance sufficient to bring its top against the connecting portion of the body, 30 but the efficacy is not materially impaired by lowering it only a portion of this distance over the pile, as shown, for example, in Fig. 1.

It will be noted that the lower edges of 35 the jaws are preferably beveled outwardly as at 45 and the inner edges of the blocks 26 and 27 are preferably beveled as at 46 which facilitates guiding the gripping device over the pile.

40 As heretofore stated the screws 30 are provided for releasing the grip of the device from the pile. If, after the pile is withdrawn, the force required to withdraw it has been sufficiently great to tightly wedge the 45 jaws into the body so that the weight of the body will not release the jaws, the screws 30 may then be operated to draw the body downwardly over the jaws a slight distance, thus permitting a slight separating movement of the jaws which releases their engagement with the pile.

Having thus described our invention what we claim is:

1. In a device of the character described, 55 a body composed of a pair of downwardly extending arms and a connecting portion,

means for attaching a pulling device to the connecting portion, downwardly converging surfaces on the inner sides of said arms, jaws slidably mounted on said surfaces, means for holding the jaws in position while permitting them to slide longitudinally of the arms, and screws carried by the body and adapted to engage the jaws to cause a movement of the body with relation to the jaws in a 60 direction opposite to the pulling force. 65

2. In a device of the character described, a body composed of a pair of downwardly extending arms and a connecting portion, means for attaching a pulling device to the 70 connecting portion, downwardly converging surfaces on the inner sides of said arms, jaws slidably mounted on said surfaces, inwardly extending shoulders at the lower ends of these arms, means for holding the 75 jaws in position while permitting them to slide longitudinally of the arms, and screws extending through said shoulders and adapted to engage the lower ends of the jaws to cause a movement of the body with 80 relation to the jaws in a direction opposite to the pulling force.

3. In a device of the character described, the combination of a bifurcated body opening downwardly, sides of the opening converging downwardly, jaws slidably mounted on these converging surfaces having adjacent gripping surfaces, means for attaching the body to a lifting device whereby the jaws may tightly engage a pile when lifting 90 force is applied, and removable blocks secured at the lower portions of the arms and projecting toward each other into the mouth of the opening, adjacent edges of said blocks being separated to admit the pile to be 95 pulled.

4. In a device of the character described, the combination of a bifurcated body having its substantially U-shaped opening, downwardly converging surfaces at the sides 100 of said opening, longitudinal grooves in said surfaces, jaws slidably mounted on the surfaces and having tongues coöperating with the grooves, a slot parallel with each groove, means rigid with each of the jaws extending 105 through said slots, and each of said means having a lateral projection slidably engaging the corresponding shoulder.

In testimony whereof, we hereunto affix our signatures.

JESSE E. WILHELM.
WILLIAM W. BONFIELD.
